UNITED STATES PATENT OFFICE.

AUGUSTUS M. SOSA AND ALBERT E. ROBINSON, OF CINCINNATI, AND HERMAN W. SCHATZ, OF NORWOOD, OHIO, ASSIGNORS TO THE AMERICAN TOOL WORKS COMPANY, OF CINCINNATI, OHIO, A CORPORATION OF OHIO.

FEEDING MECHANISM FOR METAL-WORKING MACHINERY.

1,351,970.

Specification of Letters Patent.

Patented Sept. 7, 1920.

Original application filed October 23, 1917, Serial No. 198,034. Divided and this application filed February 17, 1919. Serial No. 277,597.

To all whom it may concern:

Be it known that we, AUGUSTUS M. SOSA, ALBERT E. ROBINSON, and HERMAN W. SCHATZ, citizens of the United States, the 5 said AUGUSTUS M. SOSA and ALBERT E. ROBINSON residing at Cincinnati, in the county of Hamilton and State of Ohio, and the said HERMAN W. SCHATZ residing at Norwood, in the county of Hamilton and 10 State of Ohio, have jointly invented certain new and useful Improvements in Feeding Mechanism for Metal-Working Machinery, of which the following is a specification.

15 Our invention relates to feeding means for axially feeding a tool-spindle in metal working machinery, especially to means for automatically controlling the limits of feeding movements of the tool-spindle. We 20 have exemplified our invention as applied in a drilling machine embodying a rotatable axially movable drill-spindle.

It is the object of our invention to provide novel means for controlling the extents 25 of axial or feeding movements of the tool-spindle to predetermined depths, and for repeating the extents of predetermined axial or feeding movements of the tool-spindle; and, further, to provide novel means for 30 automatically interrupting the transmission of power in order to stop the feeding movement of the tool-spindle when at the limit of its path of movement.

The present application is a division of an 35 application for patent on improvements in feeding mechanism for metal working machinery, heretofore filed by us October 23, 1917, and given Serial No. 198,034.

The invention will be further readily 40 understood from the following description and claims, and from the drawings, in which latter:

Figure 1 is a side elevation of a portion 45 of a metal drilling machine embodying our invention.

Fig. 2 is a front elevation of a drill-head, exemplifying our invention, shown in connection with a drill-arm, the latter partly broken away, and the front of the casing 50 of the drill-head removed for exposure of the interior of the casing.

Fig. 3 is an axial section, taken on the line 3-3 of Fig. 2, illustrating the means

for adjustably controlling the extents of axial movements of the tool-spindle. 55

Fig. 4 is a plan view of the same, partly broken away.

Fig. 5 is a plan section of the same, taken in the plane of the line 5-5 of Fig. 3.

Fig. 6 is a cross-section of the same, taken 60 in the plane of the line 6-6 of Fig. 3.

Fig. 7 is a detail in cross-section, taken in the plane of the line 7-7 of Fig. 3.

Fig. 8 is a rear elevation of the controlling means for controlling the extent of 65 axial movement of the tool-spindle, partly in section in the plane of the line 8-8 of Fig. 4, and illustrating the dial set at zero.

Fig. 9 is a similar view, illustrating the relation of the parts with the dial set for 70 the limit of feeding movement of one of the divisions of feed.

Fig. 10 is a similar view, with the dial set at a position for the beginning of the second division of feeding movement of the 75 tool-spindle.

Fig. 11 is a similar view, with the dial set for the limit of the second division of feeding movement of the tool-spindle.

Fig. 12 is a similar view, showing the 80 relation of the parts, with the dial at the position of the tripping moment between the divisions of feed.

Fig. 13 is an enlarged detail of the clutch-control for the face-plate and of the clamp- 85 ing means for the index-ring, taken in section on the line 3-3 of Fig. 2.

Fig. 14 is a plan section, illustrating the clutch operating means of the feeding mechanism, taken in the plane of the line 14-14 90 of Fig. 15.

Fig. 15 is a vertical section of the same, taken in the plane of the line 15-15 of Fig. 14.

Fig. 16 is a cross-sectional detail of the 95 same, taken on the line 16-16 of Fig. 15; and,

Fig. 17 is a detail of the clutch mechanism of the feed-shaft, taken in axial section on the line 17-17 of Fig. 2. 100

The present exemplification of our invention is shown as applied to a metal drilling machine, so much of a metal drilling machine being shown as is necessary to illustrate our invention.

A tool-arm 31 has a tool-head 32 laterally 105

slidable thereon on guides 33, in any ordinary or well-known manner, as by means of a hand-wheel 34, which operates a suitable pinion coacting with a rack 35 extending lengthwise of the tool-arm. The tool-arm is arranged to be raised and lowered on a suitable column in any usual manner. The tool-head has a tool-spindle 37 therein.

Suitable means are provided for rotating 10 the tool-spindle in opposite directions, as by means of any usual or ordinary mechanism of this nature, or as described in our aforesaid application, coöperating to rotate a gear 44 selectively in opposite directions. 15 These means may include a shaft 38, extending lengthwise of the tool-arm, operated in suitable manner from the column of the machine. The gear 44 is fast on a bushing 45 journaled in a bearing 46 in the casing 47 of the tool-head. The bushing has spline-connection 48 with the tool-spindle for rotating the latter with the gear, regardless of the elevation or axial movements of the spindle.

20 25 A sleeve 51 surrounds the spindle and moves axially in a bearing 52 of the casing. The spindle rotates in the sleeve, and the sleeve is held non-rotatingly in the bearing, in usual manner, end-thrust bearings 53, 54, being between the sleeve and spindle. The sleeve is provided with a rack 55 with which a pinion 56 engages for feeding the spindle. (See Figs. 2 and 3). The pinion is fast on a shaft 57, journaled in a bearing 58 in the 30 tool-slide, and having a bushing 59 received thereabout, with which it has rotative connection, as by a key 60. The bushing extends from a face-plate 61. A worm-wheel 64 is provided with a hub 65, serving as a 35 bushing, in which the bushing 59 is journaled, the hub 65 in turn being journaled in a bearing 66 in the tool-slide.

The face-plate has arms 67 pivoted thereto at 68, for quick positioning of the spindle axially. The arms are articulated at 69 with an axially movable stub-shaft 70 having a cam-key 71 thereon, arranged to engage a lever 72 for actuating a friction-band 73 of a friction-clutch of any usual construction for fixing the worm-wheel 64 and face-plate 61 together, when it is desired to feed the spindle by means of the worm-wheel. (See Figs. 2, 3, 7 and 13). The friction-band 73 is moved radially by operation of 50 any one of the operating levers 67 outwardly for engaging the clutch, any one of said arms being movable inwardly for disengaging the clutch to manually move the drill-spindle axially, the clutch being operated by any one of said arms which may be within most convenient reach of the operator, in the same direction for producing a given result.

65 The pinion 56 is arranged to be rotated by means of the worm-wheel or by means of the

face-plate, and the worm-wheel is arranged to be rotated manually, or by a suitable speed-varying device, exemplified as comprising coöperating nests of gears 81, 82.

The nests of gears respectively comprise 70 gears of different diameters, co-operating to transmit varying speeds to an intermediate gear 84, rotatively mounted in the casing, and thence to a gear 85, the latter transmitting various speeds, 75 determined by adjustments in the speed-varying device, to a shaft 86, to which the gear 85 is fixed. The adjustments in the speed-varying device to transmit the various speeds are made by a hand-wheel 91. 80 An index-plate 92 rotates with the hand-wheel, the graduations of the index-plate co-operating with a pointer 93, to indicate the adjustment made in the speed-varying device.

85 The nests of gears are driven by a gear 95 fast with the gear 44, the latter being fixed to the bushing 45, so as to rotate therewith and with the spindle. The gear 95 meshes with a gear 96 which is the initial gear of 90 the speed-varying device. The speed-varying device exemplified is more fully shown and described and is claimed in our aforesaid application, of which this application is a division.

95 The shaft 86 is journaled in a bearing 97 in the casing, being held endwise in said bearing by means of collars 98, 99, fixed to said shaft. The shaft 86 is hereinafter termed the feed-shaft.

100 The shaft 86 is arranged to operate a worm 118, which meshes with the worm-wheel 64. The worm is also arranged to be operated by manual means, instanced as accomplished by means of a hand-wheel 119 fixed to a shaft 120, journaled in a bearing 121 of the casing, the shaft being held lengthwise in said bearing between said hand-wheel and a collar 122 fixed to said shaft. The lower end of the shaft 86 is 110 journaled in a bore 123 in the worm. (See Figs. 2 and 17). The shaft 86 is held lengthwise in the bearing 97.

115 If it is desired to operate the worm by hand, the shaft 86 is disconnected from the worm 118. This is accomplished by means of a clutch 126, shown as a tooth-clutch, the teeth being respectively on the worm and on a collar 127, having spline-connection 128 with the shaft 86. A fork 129 is received in 120 an annular groove 130 in said collar, and is fixed to a rock-shaft 131 journaled in a bearing 132 of the casing, and having an operating arm 133 secured thereto.

125 It is often desirable to cause repeated axial feeding movements of the tool-spindle to given extents, for instance when tapping threads, or boring holes, the extents of these axial feeding movements sometimes varying greatly. These axial feeds are accomplished 130

in the present exemplification by means of the worm 118 and worm-wheel 64. The worm-wheel acts on the pinion 56 for rotating the same and feeding the spindle axially. It may be instanced that a single revolution of the pinion 56 will feed the tool-spindle approximately six inches.

It often happens that a greater axial feed than is accomplished by an approximately 10 single rotation of the pinion, is desired. Means are provided in the present exemplification for causing stoppage of the axial feed at any point during a single rotation of the worm-wheel, or pinion, or during a plurality of said rotations. The stoppage of 15 the feed, in the present exemplification, is accomplished by disengagement of the clutch 126.

For accomplishing these purposes, we provide 20 the index-plate with a plurality of indexes 137, 138, instanced as on an index-ring 139 adjustable with relation to the pinion and index-plate. (See Figs. 2, 3, 4 and 13.) The ring in the present instance is 25 rotatable on a journal-face 140 of the body of the index-plate, and is arranged to be clamped in adjusted radial positions thereon by means of a clamp, which comprises a stem 142 axially movable in a bearing 143 30 of the body of the index-plate, and having a shoe 144 thereon, the clamping face of the shoe coacting with an annular inclined face 145 at the rear of the index-ring, which latter is clamped against an annular flange 146 35 on the body of the index-plate. The outer end of the stem is screw-threaded, for having threaded engagement made therewith by a handle 147. A thimble 148 surrounds said stem, a spring 149 being in the bore of said 40 thimble about said stem, for retaining resilient contact between the clamp and the index-ring when the clamp is unclamped.

The rear face of the index-ring is provided with a knock-off shoe 151 and with a 45 tripper-pin 152, the tripper-pin being instanced as projecting rearwardly farther than the knock-off shoe. (See Figs. 3, 4, 5, and 8 to 12 inclusive.)

A sleeve 153 has axial movement in a 50 bearing 154 of the tool-head, and has a rack 155 thereon, which engages a segment-rack 156, on a segment-arm 157, secured to the rock-shaft 131. This rock-shaft is the shaft which has the operating arm 133 and the 55 fork 129 thereon, the fork engaging the clutch-collar 127 of the clutch 126, for engaging or disengaging the clutch. The segment-arm is provided with a pin 161 fixed therein, the pin being provided with an apex 60 162 formed by oppositely sloping faces. A pin 163 is axially movable in a bore 164 in the tool-head and is moved toward the pin 161 by means of a spring 165. (See Figs. 3 and 14.) The pin 163 is provided with an 65 apex 166 formed by oppositely sloping faces,

the apexes 162 and 166 coacting with each other and their opposed sloping faces, for causing quick completion of the engagement or disengagement of the clutch when the apex 162 has passed the apex 166. 70

When the segment-arm has been moved sufficiently to cause the opposed sloping faces on the pins to relatively slide, so as to bring the apexes of the respective pins into line, a slight further movement of the segment-arm will cause coaction of the opposite faces of said apexes and a quick rocking movement of the segment-arm in its moving direction for either engaging or releasing the clutch 126 with a quick movement. 80

The sleeve 153 has an axially movable and rockable shank 169 therein. This shank is provided with a gage-finger 170, which is provided with an index-mark or marks, a plurality of the index-marks being provided 85 when a plurality of the indexes on the index-ring are employed. Thus the finger is provided with an index-mark 171, which coacts with the index 137, and with an index-mark 172, which coacts with the index 138. It also 90 has a handle 173 thereon for moving the shank. The shank is journaled in a bearing 174 of the casing and in the bore 175 of sleeve 153. It has a collar 176 thereon, which is fixed thereto, as by a pin 177, the collar being provided with a shoe 178, eccentric on the collar. The shoe 178 is shown as having an outer curved face upon which one of the inclined faces of the shoe 151 is arranged to ride, the parts being so arranged that when 100 the apex of the shoe 151 coacts with the outermost point on the shoe 178, the apex 162 will register with the apex 166, so as to cause the apex 162 to pass across the apex 166 at the moment of correlation between the 105 apexes of the shoes 151, 178, whereby the clutch 126 is instantly disengaged, for stopping the rotation of the feeding means for the tool-spindle.

In the present exemplification, the outer 110 index is caused to index during a single revolution of the pinion 56, this outer index being instanced as indexing depths of feed of the tool-spindle from zero to six inches. Throughout this range of feeds, rotary 115 movement of the shank 169 is not required, in fact the shank might be dispensed with and the shoe 178 fixed directly to the part carrying the segment-rack 155.

If it is desired to repeat axial movement 120 of the tool-spindle of a given extent or depth, the tool-spindle is in practice fed axially to a given point, exemplified, for instance, by the point of engagement of the point of the tool 180 with the surface of the 125 work, instanced at 181, the axial feeding of the tool being then stopped. (See Fig. 1.) The index-ring is then unclamped from the body of the index-plate and rotated, for instance by grasping the finger-knob 182 there- 130

on, until the index-mark 171 registers with the mark on the index 137, which indicates the desired depth of cut or axial movement of the tool-spindle, whereupon the clamp is again operated for clamping the index-ring to the body of the index-plate for causing the index-ring to move with the body of the index-plate. This movement is in the direction of the arrow *a*.

10 The feeding of the drill into the material is then begun, the index-plate, including its ring, rotating with the pinion 56 to rotate the worm-wheel 64, until the zero mark on the index 137 registers with the index-mark 171, at which moment the apex of the shoe 151 registers with the apex of the shoe 178, and the apexes 162, 166, of the pins 161, 163, are at the point of passage to cause quick tripping movement of the segment-rack by 15 means of the springs and consequent disengagement of the clutch 126. The operation may thereupon be repeated as many times as desired without change of relation in the index means, for again causing a similar feeding movement at the same portion of the axial movement of the tool-spindle.

If it is desired to obtain an axial movement of the tool-spindle greater than the circumferential pitch line of the pinion 56, the 20 index 138 is employed, the point of the tool being again brought to contact-position on the work. The index-ring being unclamped, it is turned until the desired depth of cut or axial movement of the tool-spindle is indicated on the inner index 138 in line with the index-mark 172, whereupon the index-ring is again clamped to the body of the index-plate. The handle 173 is then moved outwardly and turned to cause an axial and a 25 rocking movement of the shank 169. The collar 176 is provided with a tongue 183 which normally lies in a groove 184 in an enlargement 185 of the sleeve 153. The axial movement of the shank 169 moves the collar 40 and sleeve forwardly into the position shown in Fig. 4. The rocking movement of the shank causes the tongue to lie crosswise of the groove, the collar and handle being turned into the assumed positions shown in 45 Figs. 10 and 11. This turning of the shank also moves the shoe 178, which is eccentrically placed on the shank, out of the path of the shoe 151.

Fig. 10 indicates the position and relation of the parts of the knock-off shoe and pin when the feed is set for example at a depth to correspond to the beginning of the markings of the inner index, instanced as a feed of 6.001 inches.

50 In Fig. 11 the parts and the relation of the shoe and pin are indicated to represent a maximum feed within the capacity of the inner index, and is instanced as a feed of a depth of twelve inches.

65 The collar is provided with a tripper-

finger 187. When the index is set for an indication requiring more than one revolution of the index-plate to trip the clutch in order to cause cessation of feeding movement, the pin 152 will, at approximately the 70 first arrival of the zero mark of index 137 at the index-mark 171, strike the finger 187 and cause rotation of the collar 176, and the shank 169, for placing the shoe 178 in the path of the shoe 151, this relation of parts being shown in Fig. 12, it being understood that when the said collar has been rocked, as shown in Figs. 10 and 11, that the shoe 178 is out of registry with the path of movement of the shoe 151. When the index-plate completes its final rotation, the shoe 151 will coact with the shoe 178, and thereby move the shank 169 inwardly and cause inward movement of the rack 155 for rocking the segment-rack 156 and disengaging the clutch 126.

It will be noted that there is a space 189 between the zero mark and the highest mark on the outer index, and a space 190 between the lowest mark and the highest mark of 90 the inner index. These spaces represent the difference between the pitch-line circumference of the pinion 56 and a whole number. Thus, if a complete revolution of the pinion 56 represents an axial travel of the tool- 95 spindle of a fraction more than six inches, the spaces represent the fraction, which forms a gap in the index, the gap being compensated by the space 191 between the index-marks 171, 172, which would represent the angular travel of the index-plate, through said fractional space, the angular distance between the index-marks 171, 172, 100 bridging said spaces 189, 190.

The shank is provided with a screw 192, 105 serving as a pin, which is slidable in a slot 193 in the rack-sleeve, the slot having a portion which is parallel with the axis of the shank, and a portion which is at right angles thereto, the relations of the parts being preferably such that the axially extended relation between the shank and sleeve is maintained by contact of the head of the screw with the right angular portion of the wall of said slot, for relieving 110 the frictional engagement between the tongue of the collar and the outer face of the enlarged portion of the rack-sleeve. A spring 194, the ends of which are respectively secured to pins 195 and 196, respectively in a bore 197 of the shank and the bore 175 in said rack-sleeve, normally draws the shank inwardly.

Safety means are also provided for stopping the axial feed of the tool-spindle. 125 (See Figs. 14, 15, and 16.) Thus the rock-shaft 131 is provided with a bore 201 in which a rod 202 is axially movable. The rack-sleeve of the spindle is provided with a bracket 203 having a cam-face 204 there- 130

on. The rod has a pin 205 fixed therein transversely thereof. The pin is fixed to a collar 209 slidable on the rock-shaft 131. The pin slides in a slot 206 in the rock-shaft and is arranged to impinge a cam-face 207 on a cam-block 210 fixed to the drill-head, when the rod 202 is moved axially by the cam-face 204, which occurs when the drill-spindle has reached its desired lowermost limit of movement, whereby the shaft 131 is rocked by movement of the pin 205 along the cam-face 207, for disengaging the clutch 126 and stopping the feed of the spindle. A spring 208 normally urges the rod 202 toward the cam-face 204.

It is obvious that changes may be made in the exemplifications hereinbefore described within the scope of the appended claims, without departing from our invention.

Having thus fully described our invention, what we claim as new and desire to secure by Letters Patent, is:

1. In feeding mechanism for metal working machinery, the combination of a tool-spindle, feeding means therefor comprising a face-plate and a rotatable member for feeding said tool-spindle, and means for causing inactive relation in said feeding means comprising a rocking member, an axially movable slide coacting therewith, said face-plate provided with a part adjustable about the axis of rotation of said rotatable member for actuating said slide, and resilient means acting to augment said last-named actuation during the end portion of said actuation.

2. In feeding mechanism for metal working machinery, the combination of a tool-spindle, means for feeding said tool-spindle comprising a disengaging element, a face-plate and a rotatable element, and means for automatically disengaging said disengaging element comprising a rockable member having operative connection with said disengaging element, an axially movable member, rack connection between said axially movable member and said rockable member, and an actuating part for the latter adjustable about the axis of rotation of said rotatable member.

3. In feeding mechanism for metal working machinery, the combination of a tool-spindle, means for feeding said tool-spindle comprising a disengaging element, a face-plate and a rotatable element, and means for automatically disengaging said disengaging element comprising a rockable member having operative connection with said disengaging element, an axially movable member, rack connection between said axially movable member and said rockable member, an actuating part for the latter adjustable about the axis of rotation of said rotatable mem-

ber, and resilient means acting to continue disengaging movement of said rockable member after initiation of said disengaging movement by said actuating part.

4. In feeding mechanism for metal working machinery, the combination of a tool-spindle, means for axially feeding said tool-spindle comprising a clutch and a rotatable member having operative connection with said tool-spindle for feeding the same, and means for automatically stopping said feeding movement at predetermined points comprising a rock-shaft having operative connection with said clutch, an axially movable slide-member having operative connection with said rock-shaft for rocking the same, an index-ring rotatable with said rotatable member, and means for selectively connecting said index-ring and said rotatable member, said index-ring having means thereon coacting with said axially movable slide-member for axially moving the latter at a predetermined point of relation between said rotatable member and said axially movable slide-member.

5. In feeding mechanism for metal working machinery, the combination of a tool-spindle, feeding means therefor comprising a movable element, and means whereby to place said movable element in inactive relation for stoppage of feeding movement of said spindle comprising an index-member, a rotatable axially movable device for moving said movable element, said rotatable axially movable device including a manually operable part, said index-member and said device provided with coacting parts for axial movement of said device, said manually movable part having connection with one of said coacting parts to relate said coacting parts in inactive relation, and said index-member and said device provided with coacting parts for placing said last-named one of said coacting parts in coactive relation with its mating coacting part.

6. In feeding mechanism for metal working machinery, the combination of a tool-spindle, feeding means therefor comprising a movable element arranged to be placed in inactive relation for stoppage of feeding movement of said spindle, an index-plate, an axially movable slide having operative connection with said movable element for moving the same, and a rotatable stem having slide-connection with said slide, said stem provided with a finger and a contact part, and said index-plate provided with a coacting part for said finger for rotating said stem and with a coacting part for said contact part for axially moving said stem and slide.

7. In feeding mechanism for metal working machinery, the combination of a tool-spindle, feeding means for said tool-spindle, and means for causing automatic stoppage

in feeding movement of said tool-spindle comprising an axially movable member, a rotatable and axially movable member received in the latter, said members provided 5 with coacting parts for holding the same in relatively extended relation when said last-named member is rotated, and means having connection with said feeding means for rotating said rotatable and axially movable member and for axially moving both 10 said members.

8. In feeding mechanism for metal working machinery, the combination of a tool-spindle, feeding means therefor, a rocker-member 15 causing inactive relation in said feeding means, a rotatable and axially movable member having connection with said rocker-member, a face-plate and a rotatable member of said feeding means having coincident axes of rotation, tripping means rotating therewith for rotating said rotatable and axially movable member, and actuating means rotatable therewith for axially moving said rotatable and axially movable member, said tripping means and actuating means adjustable about the axis of rotation 20 of said rotatable member.

9. In feeding mechanism for metal working machinery, the combination of a tool-spindle, means for feeding said tool-spindle axially, and means for causing automatic disengagement in said feeding means for stoppage of feeding movement of said tool-spindle comprising an axially movable member 30 provided with a bore, a rotatable and axially movable member received in said bore, means for maintaining said members in extended relation upon rotation of said second-named member, and a face-plate, 35 said face-plate and second-named member provided with coacting tripping means for rotating said second-named member, said face-plate and second-named member provided with coacting actuating means, said 40 actuating means of said second-named member being out of the path of said actuating means of said face-plate when said second-named member is manually set for tripping relation, and said actuating means being 45 50 in coactive relation during tripped relation of said second-named member for causing axial movement of said second-named member upon coaction of said coacting actuating means.

55 10. In feeding mechanism for metal working machinery, the combination of a tool-spindle, means for axially feeding said tool-spindle, and means for automatically causing stoppage of feeding movement of said 60 tool-spindle comprising a driving element in said feeding means, a rocking element having operative connection with said driving element for moving the latter into inoperative relation, a rotatable and axially 65 movable member having operative connec-

tion with said rocking element for rocking the same, a rotatable element having operative connection with said feeding means, and means for adjusting said rotatable element with relation to said rotatable and axially 70 movable member, said rotatable element provided with a tripper part and an actuating part, said rotatable and axially movable member provided with a coacting tripper-part and actuating part, and said tripper parts coacting for rotating said rotatable and axially movable member for coactive relation of the actuating parts.

11. In feeding mechanism for metal working machinery, the combination of a tool-spindle, means for feeding said tool-spindle comprising a movable element and a rotatable element, a rotatable and axially movable member having operative connection with said movable element for placing the 80 same in inoperative relation, and an indexing adjustable about the axis of rotation of said rotatable element, said indexing provided with a tripper part for rotating said rotatable and axially movable member into axially movable relation and with an actuating part for automatically axially moving said rotatable and axially movable member.

12. In feeding mechanism for metal working machinery, the combination of a tool-spindle, a feed-rack therefor, a pinion meshing with said feed-rack, means for rotating said pinion comprising a movable element, a face-plate having rotative connection with 90 said pinion, said face-plate comprising a ring of an index means having a plurality of annularly arranged indices, an index-finger coacting with said plurality of annularly arranged indices, the ends of said 100 respective indices having a space between them forming gaps in said indices, said finger provided with spaced-apart marks having a space between them coincident with the angular section of said gap, said index-ring adjustable about the axis of rotation of said face-plate, and actuating means between said ring and said movable element for moving said movable element into in-active relation.

13. In feeding mechanism for metal working machinery, the combination of a tool-spindle, feeding means for said tool-spindle comprising a movable element, and means for causing stoppage of feeding movement 115 of said tool-spindle comprising an actuated member having operative connection with said movable element for placing the same in inactive relation, and a face-plate having connection with an element of said feeding 120 means, said face-plate comprising a ring of an index means provided with a plurality of annularly arranged indices, said ring adjustable about the axis of rotation of said face-plate, and said ring and said actuated 125 face-plate.

member provided with coacting means normally out of coactive relation incident to one of said indices, whereby said actuated member is caused to move said movable element into inactive relation, and with coacting means incident to another of said indices whereby to place said first-named coacting means into coactive relation.

14. In feeding mechanism for metal working machinery, the combination of a tool-spindle, feeding means for said tool-spindle comprising a movable element, and means for causing stoppage of feeding movement of said tool-spindle comprising a member having operative connection with said movable element for placing the same in inactive relation, and a rotatable face-plate having connection with an element of said feeding means, said face-plate comprising a ring 20 of an index means having a plurality of annularly arranged indices, said ring adjustable about the axis of rotation of said face-plate, and said ring and said member provided with coacting parts incident to one of 25 said indices and with coacting parts incident to another of said indices, arranged for actuation in sequence, whereby to move said movable element into inactive relation.

15. In feeding mechanism for metal working machinery, the combination of a tool-spindle, feeding means for said tool-spindle comprising a movable element, and means for causing stoppage of feeding movement of said tool-spindle comprising a rotatable member arranged to be actuated and having operative connection with said movable element for placing the same in inactive relation, and a rotatable face-plate having connection with an element of said feeding 30 means, said face-plate comprising a ring of an index device having a plurality of annularly arranged indices, said ring adjustable about the axis of rotation of said face-plate, and said ring provided with a part coacting 35 with one of said annularly arranged indices causing rotating of said rotatable member and with a part coacting with the other of 40

said annularly arranged indices for actuating said rotatable member, whereby to move said movable element into inactive relation. 50

16. In a feeding mechanism of the character described, the combination of a tool-spindle, means for axially feeding the same comprising a clutch, a rock-shaft having operative connection with said clutch for 55 causing engagement and disengagement in the same, said rock-shaft provided with a bore, an axially movable rod therein, and a relatively stationary part provided with an inclined face, said rod provided with a part 60 coacting with said inclined face by axial movement of said bar for rocking said rock-shaft, and said tool-spindle provided with a part having an abutting face for axially moving said rod proximate to the limit of 65 safe movement of the tool spindle for releasing said clutch.

17. In feeding mechanism for metal working machinery, the combination of a tool-spindle, feeding means therefor comprising 70 a feed-shaft, a clutch therefor, a face-plate, a rotatable member operated by said feed-shaft, said rotatable member arranged to contact with said face-plate in feeding said tool-spindle, and means automatically causing 75 inoperative relation in said clutch comprising a rocking member having operative connection with said clutch, and an axially movable member having operative connection with said rocking member, said face-plate provided with a part adjustable about the axis of rotation of said rotatable member for axially moving said axially movable member.

In testimony whereof we have hereunto 85 signed our names in the presence of two subscribing witnesses.

AUGUSTUS M. SOSA.
